COVER OPERATED SWITCH

Pompeo M. Santullo, Newark, N. J.

Application June 16, 1947, Serial No. 754,901

1 Claim. (Cl. 200—54)

1 This invention relates to an electrical cutout and alarm device for furnaces and the like, which burn a gaseous fuel or a fuel from which a combustible gas is likely to accumulate in the flues thereof.

In furnaces as gas burning furnaces, there exists the likelihood that unburned gas may accumulate in the flues due to the failure of the pilot or other igniter, and such accumulated gas may later become ignited causing an explosion in the furnace and flues. After the initial burning of such gases the fire may remain in the flues due to the gas being forced through the combustion chamber into the flues by the forced draught blower. This burning of the gases in the flues results in damage to the flues and furnace and any adjacent material.

It is an object of this invention to provide an automatic switch for disconnecting the blower motor and sounding an alarm when gases are ignited in the flues. Flues of this type of furnace are frequently provided with a blow-out pipe and cover to permit the escape of such ignited gases and it is an object of this invention to utilize the blow-out pipe cover as an operator for a switch to disconnect the blower motor and connect an electric alarm circuit.

Another object of this invention is to provide a device of the kind to be more particularly attached to the blow-out covers of furnaces presently installed, with little or no modifications necessary to the furnace or flues. While provided primarily as an attachment, the device may as readily be built into the furnace and flue constructions presently in progress.

A further object of this invention is to provide a switch connected selectively with either the blower motor or alarm. In normal operation the switch will complete the blower motor circuit and after a blow-out will complete the alarm circuit while breaking the motor circuit. While the device is so constructed to automatically move the switch in one direction, it may be manually reset after such automatic operation.

With the above and other objects in view, my invention consists in the arrangement, combination and details of construction disclosed in the drawings and specification, and then more particularly pointed out in the appended claim.

In the drawings,

Figure 1 is a side elevation of the electrical cutout and alarm device as attached to the blow-out pipe of a furnace.

Figure 2 is a top plan view of the switch and switch operator,

2

Figure 3 is a longitudinal section taken on the line 3—3 of Figure 2.

Figure 4 is a transverse section taken on the line 4—4 of Figure 3.

5 Figure 5 is a fragmentary side elevation, partly in section, of the switch removed from the device.

Figure 6 is a diagrammatic wiring diagram.

Referring to the drawings, the numeral 10 designates generally a furnace for burning gas, having a blower 11 driven by an electric motor 12, and having flues 14 connected to the upper end of the combustion chamber, to a chimney 15. The flue 14 includes a vertical tube 16 and a horizontal tube 17. The horizontal tube 17 is connected to the vertical tube 16 intermediate its length and communicates at one end with the chimney 15, and is open at the other end.

The open end of the horizontal tube 17 is closed with a movable cover 18. The horizontal flue 17 is known as the blow-out pipe of the furnace.

In the use of gas furnaces when the pilot lights have become extinguished, combustible gases frequently accumulate in the flues above the combustion chamber. These combustible gases in the flues may become ignited through the subsequent lighting of the pilot light, or a spark or other applied heat to the flues. Such ignition of these combustible gases results in an explosion in the flues so the cover 18 is made removable to provide an exhaust for the exploding gases, to prevent damage to the flues and to the furnace.

While the gases may accumulate in the flues 35 due to their own weight, the blowers of the furnace move the gases more quickly into the flues. It is an object of this invention to provide a means for turning off the blower motor 12 and sounding an alarm when the explosion of gases

40 in the flues occurs. The alarm and cut-off device 20, constructed according to an embodiment of this invention, comprises a switch 21 in a housing 22 fixed on the blow-out pipe 17.

The switch 21 is operated in one direction by 45 movement of the blow-out cover 18 for shutting off the motor 12 of the blower and for completing the circuit to an alarm 24. The housing 22 is rectangular in shape and open at the top, as indicated by the numeral 25. The housing 22 is 50 fixed to the free end of the blow-out pipe 17. One leaf of a hinge 26 is fixed to the outer end of the housing 22 by a rivet 27 or other suitable fastening devices. The other leaf 28 of the hinge 26 is fixed to the cover 18. The hinge leaves are 55 connected together by a pintle 29 engaging through the barrels thereof.

An upwardly extending lever 30 is fixed to the blow-out cover 18 and extends upwardly into the housing 22. The double throw switch 21 is fixed to brackets 31 which are in turn fixed to the lower wall 32 of the housing 22. The switch 21 is formed with an operating handle 33. The handle 33 is biased in both directions for completing a circuit through the pairs of contacts at each end of the switch 21. The handle 33 is formed with an opening 34 near the upper end.

A rod 35 is pivotally connected to the upper end of the lever 30 by a pivot pin 36, and loosely engages through the opening 34 of the handle 33. The end of the rod 35 which engages through the handle 33 is reduced in size to provide a shoulder 37 intermediate the length of the rod 35.

A spring 38 is coiled about the reduced end of the rod 35 and is compressible between the handle 33 and the shoulder 37. Such a connection provides a lost motion connection between the cover 18 and the handle 33 for moving the handle in one direction upon movement of the cover, and the spring 38 constantly urges the cover 18 to its normally closed position.

For resetting the switch 21, a reset rod 39 is pivotally carried by the handle 33. The reset rod 39 is pivotally connected between ears 40 intermediate the length of the handle 33, by a pivot pin 41. The rod 39 extends rearwardly and through an opening 42 in the rear wall of the housing 22. A handle 43 is fixed on the rear end of the rod 39 so that the handle 33 may be moved in either direction by an operator from outside of the housing 22.

In the use and operation of this device, when an explosion occurs within the blow-out pipe 17, the blow-out cover 18 is suddenly pivoted about the hinge pin 29. The upper end of the lever 30 is then moved rearwardly and as the spring 38 is compressed the handle 33 of the switch 21 is moved to its rear position. In the rear position of the handle 33, the circuit to the motor 12 is broken and the electric circuit to the alarm 24 is completed. When the switch 21 is reset by the movement of the switch 33 to its original position, the alarm circuit is broken and the motor circuit re-connected. The spring 38 is normally slightly

compressed with the switch 21 in the motor circuit position. When the handle 33 is in the position for closing the circuit to the alarm, there still remains some tension on the spring 38 for urging the cover 18 back to the closed position.

I do not mean to confine myself to the exact details of construction herein disclosed, but claim all variations falling within the purview of the appended claim.

10 What I claim is:

15 Switch operating mechanism for a safety system for a furnace having a blower motor, a blow-out pipe, a pivoted cover therefor, and a double throw switch closing a blower motor circuit in one position thereof and opening said motor circuit and closing an alarm circuit in another position thereof; comprising a housing for mounting on the blow-out pipe adjacent the pivoted cover and engageable over the switch, a lever rockably carried by said housing and having one end adapted for connection to the pivoted cover, a rockable handle having one end adapted for connection to the switch, an opening formed through the other end of said handle, an actuating rod pivotally connected at one end thereof to the other end of said lever, a portion of reduced thickness formed on the other end of said rod slidably extending through said handle opening, a coil spring member disposed about said portion of said rod and bearing against said handle, and a reset rod extending slidably through a wall of said housing and having the inner end thereof pivotally connected to said handle.
